UNITED STATES PATENT OFFICE.

HOYT CATLIN, OF FAIRFIELD, CONNECTICUT, ASSIGNOR TO THE BRYANT ELECTRIC COMPANY, OF BRIDGEPORT, CONNECTICUT, A CORPORATION OF CONNECTICUT.

ELECTRIC SWITCH.

Application filed July 14, 1921. Serial No. 484,738.

To all whom it may concern:

Be it known that I, HOYT CATLIN, a citizen of the United States of America, residing at Fairfield, in the county of Fairfield and State of Connecticut, have invented certain new and useful Improvements in Electric Switches, of which the following is a specification.

My invention relates to electric switches, and particularly to circuit selector switch installations such as are used for example, to distribute the current in different paths through a heater unit of an electric range, toaster or other appliance of similar character. The object of my invention is to provide a device in which a master switch is associated with a selector switch, with which it is so interconnected that while the position of the selector switch may be changed at will when the master switch is in "off" position, and no current is flowing, on the contrary, the selector switch connections cannot be changed while the master switch is in "on" position, and current is flowing. The underlying conception of the invention is subject to embodiment in many different forms of construction, only some of which are indicated in the accompanying drawings, in which

Fig. 1 is a plan view of a switch in which my invention is embodied;

Fig. 2 is a similar view with the face plate removed;

Fig. 3 is a section on the line 3—3, Fig. 2;

Fig. 4 is a side elevation thereof partially broken away;

Fig. 5 is a skeleton view of the insulating base illustrating the connections between the various switch contacts;

Fig. 6 is a broken section on the line 6—6, Fig. 2;

Figs. 7 and 8 are elevations of the distributing switch in different positions;

Figs. 9 to 12 inclusive are diagrams illustrating the circuit in the different positions of the selector switch;

Figs. 13, 14 and 15 are diagrammatic illustrations of various modifications of construction in which my invention is embodied.

While a switch installation of the present type may be utilized for various purposes and suitably modified for different utilities,

I have illustrated a construction adapted to control the different circuits through the resistance elements of a standard heater unit adapted to give high, low and medium heats. Such units are common in electric ranges and electric heating appliances of various sorts.

The installation normally includes a front or casing element, indicated by the plate 20, through which project the operating handle 21 for the master switch and the operating handle 22 for the selector switch. Adjacent the apertures 23 and 24 in the plate through which the switch handles pass, are suitable legends 25 and 26, so related to the handle, or other moving element of the switch mechanism, as to afford an indication of the position of the respective switching members thereto.

The particular shape and construction of the insulating base or bases upon which the switches are mounted is of secondary moment, so long as the interlocking elements of their mechanisms are positioned to function properly. As here shown, however, the base 27 is unitary and carries at one end a master switch generally designated by the reference A, and at its other end a selector switch, generally indicated by the reference B. At one end of the base, and adjacent the master switch are terminals 28 and 29 for connection to the wire mains. At the opposite end of the base are terminals 30, 31 and 32 for connection to the distributing wires. The wire terminals 28 and 29 are suitably connected by straps 33 and 34 (Fig. 5) to the switch contacts 35 and 36 respectively, of the master switch, which is of double pole type. The cooperating switch contacts 37 and 38 are respectively connected by straps 39 and 40 to the contacts 41 and 42 of the selector switch, which is also provided with auxiliary contacts 43 and 44. Contacts 41, 43 and 44 of the selector switch are respectively connected to the wire terminals 30, 31 and 32 by straps 45, 46 and 47.

The master switch A is of standard construction and need not be further described than to specify that it is of the high capacity, quick make and break type. Its toggle mechanism includes the oscillating rocker 48, for actuating the switch mechanism. Associated with the rocker is a recipro-

eating locking bar 49, which is apertured at 50 to accommodate the rocker and is provided with a cross web 51 slidably engaged in the notch 52 of the rocker. The interlocking bar 49 is supported upon posts 53 and 54, upon which it is guided by the screw pins 55 and 56 working in slots 57 and 58 in opposite ends of the bar. At one end the bar is provided with a stud 59.

10 The selector switch B, which may also be of any suitable construction, is shown as comprising an insulating disk 60, the peripheral lug on which forms the operating handle 22. The disk is mounted on a pivot pin 61 extending between the standard 53 and the standard 62, and rocks thereon in a plane at right angles to the plane in which the interlocking bar 49 reciprocates. It carries a diametral switch bar 63, adapted 15 to bridge the distributing contacts 41 and 44. It also carries a segmental bar 64 adapted to bridge either the contacts 42 and 43, or the contacts 42 and 44, depending upon the position of the switch. In the position 20 in which the bar 63 bridges the contacts 41 and 44, the bar 64 simultaneously bridges the contacts 42 and 43. In the position in which the handle 22 is rocked to the right and the diametral bar 63 is out of engagement with its cooperating contacts, the segmental bar 64 spans the contacts 42 and 43 (Fig. 7). When the disc is rocked in the opposite direction (Fig. 8) only the contacts 42 and 44 are connected by the segmental 25 bar 64. In order to accurately locate the selector switch in its several positions, I provide a disc with a lug 65, which in the position of the switch shown in Fig. 6, is engaged and detained by the spring 66 mounted at the bottom of a channel 67 in 30 the base. A second lug 68 projecting from the disc 60 impinges against the base 27 (Fig. 7) to halt the oscillation of the disc in the position in which the segmental bar 64 35 bridges the contacts 42 and 43. The lug 65 impinging against the end wall of the recess 67 serves to halt the disc 60 in the position in which the contacts 42 and 44 are connected (Fig. 8).

40 The three different positions of the disc 60 in its three selector circuit connections, are thus accurately predetermined for the purpose of insuring a locking engagement therewith by the stud 59 of the interlocking bar 49 when the master switch is thrown to circuit-closing position. To receive this stud 45 the face of the disc 60, adjacent the master switch, is recessed or apertured at 69, 70 and 71. These apertures are so located that 50 when the selector switch is in each of its three positions, one or the other of the recesses 69 to 71 lies in register with the stud 59. Consequently, when the rocker 48 of the master switch is thrown to "on" position, the interlocking bar 49 is advanced

sufficiently to enter the stud 59 into one or the other of the recesses in the selector switch disc 60. Obviously so long as the master switch remains in circuit-closing position, the interlocking bar prevents operation of the selector switch. It is furthermore clear that when the master switch is thrown to "off" position, the distributing switch may be rocked freely to any position which the attendant may desire it to occupy 75 when the current is again thrown "on" by the closing of the master switch.

In view of the fact that the position of the selector switch cannot be altered while the master switch is in circuit-closing position, it is unnecessary that the distributing switch be of the quick make and break type, since it is always in circuit-closing position when the circuit is established therethrough. Furthermore, inasmuch as the duty of the master switch is merely to control the flow of current, it is relieved of the structural complications incident to the combination of a master switch and selector switch in a single unitary structure. The mechanism 85 and arrangement of parts may thus be made far simpler than is customary in heater switches, and it may be of any standard type having a breaking capacity sufficient to safely handle the current of the heater 95 circuit.

As has been stated, the master switch may be of any suitable standard type. It is also true that the distributing switch may be variously modified. Thus, in Fig. 13 100 the master switch 72 is diagrammatically indicated as of the standard rotary snap switch type, the details of which are not illustrated, since they are well known. The selector switch 73 is also of the rotary type 105 and comprises an insulating disc which carries switch bars 74, 75 and 76 adapted to cooperate with suitably arranged contacts 77, 78, 79 and 80, to which in the different 110 positions of the disc 73 the current is distributed in the same manner as is diagrammatically illustrated in Figs. 9 to 12 inclusive in connection with the previous construction. The spindles 81 and 82 of the two switches are of course arranged in fixed 115 position in predetermined relation to each other. The interlocking connection between the switches is afforded by a rocking lever 83, one end of which bears against the cam 84 on the spindle of the master switch, while the other end is provided with a stud or dog 85 adapted to enter one or the other of the notches 86, 87 and 88 of the disc 89 mounted on the spindle of the selector switch and moving with the latter and with 120 its handle 90. Obviously, when the master switch 72 is turned to "on" position, the cam 84 shifts the tilting lever 83 to force its dog 85 into one or the other of the notches 86 to 125 89, thus holding the distributing switch 130

in fixed position. When the master switch is again turned to "off" position, the dog 85 is withdrawn from the notch by the outward movement of the lever under the influence 5 of the spring S.

Fig. 13 indicates the position of the selector switch, with the contacts which establish a high heat circuit connected by the bars 74 and 75. In Fig. 14 the position of the 10 selector switch has been shifted to establish connection between the contacts which afford a medium heat circuit connection. As will be noted, the operating handle 90 of the selector switch serves also as an indicator associated with the legends 91 suitably arranged upon the casing or cover plate above which the handle 90 lies.

It is obvious that a rotary selector switch of this type may be quite as readily associated with a master switch of the type shown 20 in Figs. 2, 3 and 4, if the notches in the locking disc 89 be so located that the lock bar 49 of the master switch engages them when the latter is thrown to circuit-closing position.

In Fig. 15, another modification of the selector switch is shown, while the master switch is of the double push-button type. The interlocking bar 92 is of substantially 30 the same character as that first described, having an operating connection at 93 with a lug on the rocker 94 of the master switch. The selector switch is of the push and pull type and may comprise a block 95 of insulating 35 material, carrying one or more contact plates 96 which establish connection with the several distributing contacts 97 in different positions. Notches 98 in the side of the plug facing the master switch are engaged by the interlocking bar 92 when the 40 master switch is in circuit-closing position, thus holding the selector switch against change of position until the master switch is again thrown to circuit-opening position.

It is clear from the foregoing that there are various possible embodiments of the underlying basic conception of the invention. My underlying thought may be briefly stated to reside in the combination of a 45 master switch and a selector switch, with means operated by the master switch to prevent operation of the selector switch when the master switch is in circuit-closing position. Specifically, it resides in the combination of a quick make and break master switch with a slow make and break selector switch, so related that the selector switch cannot be operated until the master switch is opened. The invention is not therefore 55 confined to the particular constructions shown, but is susceptible of many variations.

within the scope of what I claim as my invention.

I claim—

1. A switch device comprising a pair of wire terminals for connection to the mains, a group of wire terminals for connection to distributing lines, switch contacts permanently connected to the main terminals, cooperating switch contacts spaced therefrom, switch bars affording a double make and break connection between said switch contacts, a master snap switch mechanism for operating said bars, together with switch contacts permanently associated with the distributing terminals, a multi-position selector switch for establishing connection between certain of said contacts, permanent connection between certain of said contacts and the distributing contacts of the master switch, together with means operated by mechanism of the master switch for locking the selector switch against movement when the master switch is in circuit-closing position.

2. A switch device comprising an insulating base, a master switch and a selector switch mounted thereon, permanent connections between certain of the master switch and certain of the selector switch contacts, binding terminals connected to other of the master switch contacts and certain of the selector switch contacts, a double break snap switch mechanism for closing and opening the circuit through the master switch, a selector switch circuit closer, and means operated by the mechanism of the master switch for locking the circuit closer of the selector switch against actuation when the master switch is in circuit-closing position.

3. A switch device comprising a master switch and an associated distributing switch, a manually operated rocking member for actuating the master switch, a manually controlled oscillating member for actuating the selector switch, the axis of oscillation of said manually controlled member of the oscillating switch lying substantially in the plane of oscillation of the actuating member of the master switch, together with a reciprocating locking member moving with the manually operated member of the master switch and engaging the manually operated member of the selector switch to hold the latter against operation when the master switch is in circuit-closing position.

In testimony whereof I have signed my name to this specification.

HOYT CATLIN.
